CASING FOR WATER HEATERS

Application filed February 4, 1928. Serial No. 251,776.

Our invention relates to casings for water heaters, and has for an object the provision of a simple and inexpensive casing, which is light in weight, very strong and durable, and which is capable of withstanding rough handling without distortion.

Other objects and advantages will become apparent as this description progresses and by reference to the drawing wherein,—

10 Figure 1 is an elevated view, partially in section, of one form of heater embodying our invention.

Fig. 2 is a horizontal section taken substantially on line 2—2 of Figure 1.

15 The particular form of water heater which we have chosen to illustrate our invention embodies an inner wall or casing 5 which is closed at the top and bottom to provide a water storage tank. This storage tank is 20 surrounded by a cylindrical metal insulating jacket or casing 6 spaced therefrom to provide an insulating space 7. This insulating space may be employed as a dead air space or may be filled with a suitable insulating 25 material such as asbestos or the like. The casings 5 and 6 are extended downwardly to provide a combustion chamber 8 beneath the storage tank which may enclose water heating and circulating elements of any desired 30 form. The foregoing structure is mounted upon a base 9 which is supported by the usual legs 10. The upper part of the structure is closed by a cover 11 through which pass the usual water supply and service connections 35 12 and 13 and the flue structure 14.

From a standpoint of economy in manufacture and to provide a heater structure which is not excessively heavy, it is desirable that comparatively light weight materials 40 be employed in forming some of the heater parts, and particularly the outer shell or casing 6. To this end, the casing 6 may be formed of relatively thin and light weight 45 sheet metal material. However, unless otherwise provided for, it has been found that such a thin metal casing is readily susceptible of distortion in case of ordinary rough handling during assembly, packing, shipping and 50 installation with the result that considerable

loss may be experienced in repairing or replacement of the injured casing.

The principal feature of our invention is to provide a thin and light weight metal heater casing which is capable of withstanding ordinary rough handling without injury. We provide the casing 6 at intervals around its circumference with a plurality of exteriorly projecting longitudinal ribs 15, which preferably, but not necessarily, take the cross-sectional shape shown in Fig. 2. We have found that, by arranging these ribs in spaced groups, the shell is strengthened and made capable of withstanding ordinary impacts without distortion. Such shell is capable of withstanding strains and stresses without distortion when applied from any direction. Furthermore, by pressing these ribs outwardly from the metal wall, as shown, an added rigidity effect is produced and any tendency of the shell wall to collapse is efficiently opposed.

We have shown three ribs in each group, such ribs being of, at least, two distinct shapes in cross-section; however, it is to be understood that both the number of the ribs and their shapes may be varied without departing from our invention. It is to be further understood that our invention is not limited to the form of heater shown in the drawing. It will be appreciated that these ribs may be readily applied to the wall of a storage tank such, for example, as the wall 5 of the storage tank shown in the drawing.

We claim:

A water heater storage tank comprising an elongated vertically disposed inner casing closed at the top and bottom to provide a storage tank, an outer cylindrical elongated vertically disposed metal insulating casing spaced therefrom to provide an insulating space, said inner and outer casings being extended downwardly to provide a combustion chamber beneath the storage tank, said outer casing being provided with a plurality of spaced groups of longitudinal ribs formed in the circumference of said casing and extending throughout the length thereof, some of said ribs in each group being of different shape in cross section, said groups of ribs

imparting strength to the outer casing to prevent collapsing thereof and serving further to slenderize the appearance of the heater tank.

5 In witness whereof, we have subscribed our names.

SIMON J. LONERGAN.
LEE P. CORSBIE.
